UNITED STATES PATENT OFFICE.

JOHN MÉSZÁROS AND FRANK MOLNÁR, OF GLENALUM, WEST VIRGINIA.

RAIL FASTENER.

1,404,992.

Specification of Letters Patent. Patented Jan. 31, 1922.

Application filed October 15, 1921. Serial No. 507,973.

To all whom it may concern:

Be it known that we, JOHN MÉSZÁROS and FRANK MOLNÁR, citizens of Hungary, residing at Glenalum, in the county of 5 Mingo and State of West Virginia, have invented certain new and useful Improvements in Rail Fasteners, of which the following is a specification.

This invention relates to rail fasteners 10 such as are used on railroad tracks to secure the rails in place.

The invention has for an object to provide a novel form of rail fastener by means of which the rail will be securely held in place.

For further comprehension of the invention, and of the objects and advantages thereof, reference will be had to the following description and accompanying drawings, and to the appended claims in which 15 20 the various novel features of the invention are more particularly set forth.

Fig. 1 of the drawings is a side view of a portion of a railroad track having the invention applied thereto.

Fig. 2 is a transverse vertical section on the line 2—2 of Fig. 1.

Fig. 3 is a detail plan view of one of the rail fastening members.

Fig. 4 is a longitudinal section on the line 30 4—4 of Fig. 3.

Fig. 5 is an enlarged fragmentary transverse section on the line 5—5 of Fig. 4.

In the drawings the reference numeral 10 indicates the rails of a track, which are of 35 ordinary construction. The sleepers, or ties, on which the rails rest are indicated at 11 and preferably comprise metal I-beams.

The fastening means for each rail comprises a pair of bars 12 extending longitudinally of the tie 11 and located at opposite sides thereof to leave a space for the rail engaging members, the rails 10 resting upon these bars. These bars 12 are suitably placed longitudinally of the tie, being here 40 45 shown as flush at their outer ends with the adjacent ends of the tie, and being of a length somewhat greater than the width of the base-flange of the rail. These bars have their adjacent faces beveled downwardly 50 away from one another, thus forming a dovetail slot to receive the rail engaging members. The bars 12 may be secured to the tie 11 by means of rivets 13 passing through the ends thereof and through the 55 flanges of the latter.

Each of the bars 12 has a pair of semi-

circular integral ears 15 projecting upwardly therefrom on opposite sides of the rail 10, these ears being spaced apart, longitudinally of the bars, a distance equal to 60 the width of the base-flange of the rail so as to engage the sides of the same and prevent transverse displacement of the rail.

The rail 10 is locked against upward movement by means of a pair of suitably shaped claws 16 which engage over the opposite sides of the base-flange of the rail, these claws being formed integrally with base-plates 17 located and slidably in the dovetail slot between the bars 12, the inner 65 70 halves of these base plates project under the rail with their ends in abutting engagement, while the claws 16 project upwardly and inwardly from the outer halves of these plates.

To prevent transverse displacement of these locking members 16, 17, we provide bolts 20 which are passed through suitable registering apertures therein and in the ears 15. The bolts 20 are preferably held against 80 withdrawal by means of cotter pins 21 passed through their unheaded ends. To prevent these cotter pins being pulled out by unauthorized persons we preferably cover the same with caps 23 hinged as at 24 85 to the adjacent bar 12, each of these caps having a double-back spring latching element 25 which projects into a recess 26 in the ear 15 and engages a lip 27 at the front thereof. This lip is slotted as shown so that 90 a pointed implement may be inserted therein, over the end of the latch 25, and press the same downward to release the cap.

The abutting inner ends of the base-plate elements are also preferably secured together by means of a stud 30 on one element which engages in a socket in the other element, a screw 31 being threaded transversely through the last element and passing through a registering aperture in the stud. 95 For access to the screw 31 an opening 32 is provided in one of the bars 12.

Having thus described our invention what we claim as new and desire to protect by Letters Patent of the United States is as 105 follows:

1. In combination, a railroad track tie, a pair of bars fixed to the top thereof, said bars being spaced transversely of the tie and extending longitudinally thereof, a pair 110 of base-plate elements slidably engaged between said bars and arranged end to end and

having integral claws adapted to engage over the base flange of a rail, bolts passing through said bars and base plates, cotter pins passing through said bolts, and caps 5 hinged to said bars and covering said cotter pins.

2. In combination, a railroad track tie, a pair of bars fixed to the top thereof, said bars being spaced transversely of the tie and 10 extending longitudinally thereof, a pair of base-plate elements slidably engaged between said bars and arranged end to end and having integral claws adapted to engage over the base-flange of a rail, said bars having each a pair of upstanding ears spaced 15

therealong a distance equal to the width of the base-flange of the rail, and bolts passing through said ears and said base-plate elements to secure the latter to the said bars, a stud projecting from the inner end of one of 20 said base-plate elements into a socket in the inner end of the other base-plate element, and a screw threaded through the last mentioned base-plate element and passing transversely through said stud.

25 In testimony whereof we have affixed our signatures.

JOHN MÉSZÁROS.
FRANK MOLNÁR.
